AUTOMATIC GRIP FOR LIFESAVING
DEVICES

Jack Frankel, Brooklyn, N. Y.

Application July 1, 1944, Serial No. 543,069

11 Claims. (Cl. 24—135)

This invention relates to new and useful improvements in a life saving device.

More specifically, the invention proposes the construction of a novel type of clamp for use in a life saving device for persons working in elevated positions on scaffolds and the like and arranged in a manner to be engageable with a safety belt and an adjacent guy rope.

Still further it is proposed to characterize the clamp by a bracket supporting movable jaws engageable against opposite sides of the guy rope.

A further object of the invention proposes a novel means for supporting the movable jaws upon the bracket in a manner to be movable towards each other for rigidly clamping the guy rope.

Still further, it is proposed to provide novel means for moving the slidably mounted jaws toward each other and which is arranged in a manner to permit the clamping action to be quickly effected.

Still further the invention contemplates a clamp as aforesaid having an adjustable jaw and an automatically closable jaw.

Still further the invention contemplates an automatic clamping device which will automatically reclose one slidably mounted jaw onto the guy rope, forcing it into engagement with the adjustably mounted jaw in the event of an emergency. With this arrangement it is impossible for a person using the device to experience a fall of any distance. If a fall should start, it would be arrested immediately.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of a clamp or a device constructed in accordance with this invention.

Fig. 2 is a rear view of the clamp of Fig. 1.

Fig. 3 is a plan view of the clamp of Fig. 1.

Fig. 4 is an end view of the left side of the clamp shown in Fig. 1.

Fig. 5 is a perspective view of one of the jaws of the clamp of the present invention.

Fig. 6 is a section on the line 6—6 of Fig. 1.

Fig. 7 is a section on the line 7—7 of Fig. 1.

Fig. 8 is a perspective view illustrating a man standing upon a scaffold and using a life saving

device constructed in accordance with this invention.

Fig. 9 is a perspective view of the assembled life saving device per se.

Fig. 10 is a developed view of the waist engaging belt, per se.

Fig. 11 is an end view showing a clamp constructed in accordance with a modification of this invention, the view being taken from the left side of the clamp.

Fig. 12 is a section on the line 12—12 of Fig. 11.

The life saving device, in accordance with this invention, includes a belt 10 for engagement about the waist of a person operating from a suspended scaffold 11. The belt 10 is of conventional construction and includes a buckle 12 on one end. The buckle 12 has a pivotal tongue 13 selectively engageable with one of a plurality of openings 14 formed in the other end of the belt. Attached at spaced positions along the length of the belt 10 there is provided a pair of leg engaging straps 15 which are arranged to engage the top of the wearer's legs immediately adjacent the crotch. The positioning of the belt 10 and straps 15 upon the waist of a person is clearly illustrated in Fig. 8 of the drawings.

A clamp 16 is adapted to be attached to the belt 10 and a guy rope 17 projected downwards adjacent the scaffold 11. The clamp 16 is characterized by a base or bracket 18 having a pair of downwardly extending eye pieces 19. Each of the eye pieces is provided with a downwardly extending fastening means by which the bracket 18 is attached to the belt 10.

Each of the fastening means is characterized by a flexible cable 20 projected through and having its ends secured to a rigid tube member 21 which acts to encase its cables. Mounted upon each of the cables adjacent the lower end of the tube members 21 there is a clamp 22 having a spring closed jaw 23. These clamps 22 are engaged with complementary rings 24 securely mounted upon the belt 10 at points adjacent the straps 15.

Clamp 16 further has an end wall 25 bolted to the bracket 18. A threaded orifice 26 is formed in wall 25 and a screw 27 is threaded through this orifice. A set screw 28 is provided for selectively locking and unlocking screw 27 in orifice 26. A handle 29 is fastened to one end of the screw 27 and a movable jaw 30 is mounted on the other end of the screw 27, screw 27 having an annular slot 31 in which a pin 32 projects, securing the jaw on the screw 27 but permitting the screw to rotate relative to the jaw.

Jaw 30 has slots 33 in which are disposed bolts 34 screwed into the bracket 18 and slidably mounting the jaw on the bracket. Washers 35 are provided adjacent the slots. A rope-engaging serrated vertical groove 36 for engaging one side of the guy rope 17 is provided in one side face of the jaw.

A similar but oppositely directed jaw 37 is secured to the bracket 18 by bolts 34' disposed in slots 33'. However, a shaft 38 is secured in jaw 37 instead of a screw 27. Shaft 38 extends to the end of the clamp 16 remote from the handle 29 and is journaled at this end in an end wall 39 secured to two vertically spaced members 40 which in turn are bolted to the rear face of the adjacent end of the bracket 18.

Wall 39 has an inwardly extending boss 41 in which is the orifice forming the bearing for the adjacent end of shaft 38. A collar 42 is journaled on shaft 38 adjacent boss 41 and a movable handle 43 is secured to this collar. A stationary handle 44 is bolted to the back of the members 40 in line with handle 43. A torsion spring 45 is mounted on shaft 38 with one end secured to collar 42 by a bolt 46. A coil spring 47 is connected at one end to the top member 40 by a screw 48 in line with collar 42 and at the other end to the bolt 46 by a pin 49. Spring 47 augments spring 45. The other end of spring 45 is secured by a bolt 50 to an end wall 51 similar to wall 25 and bolted to bracket 18 at the adjacent end thereof. While wall 51 is an end wall of the bracket 18 it is an intermediate wall of the clamp. However, as members 40 may be, if desired, parts of bracket 18, in the appended claims walls 25 and 39 will be considered the end walls of the bracket and wall 51 an intermediate wall.

A cam 52 is secured to shaft 38 by a pin 53 adjacent wall 51 and a cam 54 is rotatably mounted on shaft 38 and secured to jaw 37. Two small tension springs 55 connected to jaw 37 and end wall 51 operate to hold cams 52 and 54 in engagement.

The operation of the device is as follows:

A person about to work upon a scaffold similar to that shown at 11 in the drawings, engages the belt 10 about his waist. When the straps 15 are engaged about the top of the person's legs the clamps 22 of the clamp 16 are then engaged with the rings 24 mounted on the belt 10. The set screw 28 is then loosened and the jaws separated so that the guy rope 17 can be placed between the jaws 30 and 37 of the clamp 16. The handle 29 is then turned to move the screw 27 inwardly and thus move the jaw 30 towards the jaw 37 to firmly grip the guy rope between the jaws whereupon the set screw 28 is screwed in again. The springs 45 and 47 maintain the jaw 37 in position so that the guy rope is firmly gripped by the two jaws, jaw 37 being prevented from moving due to the engagement of the cams 52 and 54. With the lift saving device thus assembled, it will be noted that it is practically impossible to fall to the ground in the event that a person loses his foot hold on the scaffold, or if one of the ropes from the scaffold should break, as the guy rope is firmly held by the clamp 16, the serrations of the jaws forming a tight grip.

If it is desired to hoist or lower the scaffold and it becomes necessary for the clamp 16 to be moved upward or downward upon the guy rope 17, it is merely necessary for the person to which the clamp 16 is attached to grip the handles 43 and 44 and squeeze them together. This can be

done with one hand. This operation will rotate collar 42, tighten spring 45, stretch spring 47, rotate shaft 38 and cam 52. Rotation of cam 52 will cause a space to be formed between the cams and the springs 55, which are under tension, will move jaw 37 away from jaw 30, freeing rope 17 in the jaws so that the clamp 16 may be slid relative to the rope without the rope leaving the jaws.

When the clamp has been moved to its new proper position, the person using the clamp need only release the handles 43 and 44 to cause the clamp 16 to again grip the rope 17. That is to say, the regripping of the rope by the jaws is automatic, which is an important feature of the present invention, for should the user of the clamp fall while adjusting the clamp on the guy rope, he need only release his grip on the handles to make the clamp 16 regrip the guy rope to stop the fall. This automatic regripping is caused by the unwinding of the spring 45 and the return of spring 47 to normal position, which rotates shaft 38 backward and causes cam 52 to rotate and reengage cam 54, moving jaw 37 toward jaw 30.

It is contemplated that when handles 43 and 44 are gripped and moved together to free rope 17 for sliding, rope 17 is nevertheless maintained in the grooves 36 and 36' and the jaws do not open sufficiently to permit the rope to move out of the jaws. This is an added safety feature of the present device.

Springs 45 and 47 augment each other and either of these springs may be eliminated if desired, although it is a desirable safety feature to include both springs so that a positive spring action will always be present and the failure of either spring will not make the device inoperative.

The pressure exerted on the rope by the springs 45 and 47 is always constant. However, the effective pressure that these springs exert may be controlled by the movable jaw 30. That is to say, jaw 30 may be moved to a position nearer jaw 37 to increase the pressure with which the guy rope is held or moved away to decrease the pressure. It further provides for better operation on ropes of different diameters.

In the modification of the invention shown in Figs. 11 and 12, a clamp is shown which is substantially like the clamp 16 except that the handle 43' is connected to an internally toothed ring gear 56 having slots 57 in which are disposed bolts 58 securing the ring gear to the end wall 39' for limited rotation relative thereto. A gear 59 is secured on the end of shaft 38' in engagement with the teeth of ring gear 56. Rotation of the handle 43' rotates ring gear 56 and thereby gear 59 and shaft 38', this rotation of shaft 38' being accompanied by the same results as the rotation of shaft 38 and no further description thereof is deemed necessary.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. In a device of the class described, a clamp, comprising a bracket, a jaw having a serrated rope-engaging groove movably mounted on said

bracket, a screw threaded into a part of said bracket and rotatably secured to said jaw for adjusting the position of said jaw, another jaw having a serrated rope-engaging groove complementary to said first mentioned groove movably mounted on said bracket, a shaft rotatably journalled at one end in said other jaw and at its other end in a part of said bracket, a cam rotatably mounted on said shaft and secured to said other jaw, another cam rigidly secured on said shaft and adapted to engage said jaw cam for moving said other jaw toward said adjustable jaw, a handle secured to said shaft for rotating same manually to disengage said cams to permit said other jaw to move away from said adjustable jaw, and a spring means operatively connected to said shaft and to said bracket for automatically rotating said shaft in a reverse direction when said handle is released to move said other jaw toward said adjustable jaw.

2. In a device of the class described, a clamp, comprising a bracket, a jaw having a serrated rope-engaging groove movably mounted on said bracket, a screw threaded into a part of said bracket and rotatably secured to said jaw for adjusting the position of said jaw, another having a serrated rope-engaging groove complementary to said first mentioned groove movably mounted on said bracket, a shaft rotatably journalled at one end in said other jaw and at its other end in a part of said bracket, a cam rotatably mounted on said shaft and secured to said other jaw, another cam rigidly secured on said shaft and adapted to engage said jaw cam for moving said other jaw toward said adjustable jaw, a handle secured to said shaft for rotating same manually to disengage said cams to permit said other jaw to move away from said adjustable jaw, and a spring means operatively connected to said shaft and to said bracket for automatically rotating said shaft in a reverse direction when said handle is released to move said other jaw toward said adjustable jaw, said spring means including a torsion spring disposed around said shaft.

3. In a device of the class described, a clamp, comprising a bracket, a jaw having a serrated rope-engaging groove movably mounted on said bracket, a screw threaded into a part of said bracket and rotatably secured to said jaw for adjusting the position of said jaw, another having a serrated rope-engaging groove complementary to said first mentioned groove movably mounted on said bracket, a shaft rotatably journalled at one end in said other jaw and at its other end in a part of said bracket, a cam rotatably mounted on said shaft and secured to said other jaw, another cam rigidly secured on said shaft and adapted to engage said jaw cam for moving said other jaw toward said adjustable jaw, a handle secured to said shaft for rotating same manually to disengage said cams to permit said other jaw to move away from said adjustable jaw, and a spring means operatively connected to said shaft and to said bracket for automatically rotating said shaft in a reverse direction when said handle is released to move said other jaw toward said adjustable jaw, said spring means including a coil tension spring.

4. In a device of the class described, a clamp, comprising a bracket, a jaw having a serrated rope-engaging groove movably mounted on said bracket, a screw threaded into a part of said bracket and rotatably secured to said jaw for adjusting the position of said jaw, another hav-

ing a serrated rope-engaging groove complementary to said first mentioned groove movably mounted on said bracket, a shaft rotatably journalled at one end in said other jaw and at its other end in a part of said bracket, a cam rotatably mounted on said shaft and secured to said other jaw, another cam rigidly secured on said shaft and adapted to engage said jaw cam for moving said other jaw toward said adjustable jaw, a handle secured to said shaft for rotating same manually to disengage said cams to permit said other jaw to move away from said adjustable jaw, and a spring means operatively connected to said shaft and to said bracket for automatically rotating said shaft in a reverse direction when said handle is released to move said other jaw toward said adjustable jaw, said spring means including a torsion spring disposed around said shaft and a coil tension spring.

5. In a device of the class described, a clamp, comprising a bracket having a back, end walls and an intermediate wall, a jaw having a serrated rope-engaging groove movably mounted on said bracket back wall, a screw threaded through one of said bracket end walls and rotatably secured to said jaw for adjusting the position of said jaw, another jaw having a serrated rope-engaging groove complementary to said first mentioned groove movably mounted on said bracket back wall, a shaft rotatably journalled and secured at one end in said other jaw and at its other end journalled in the other end wall of said bracket, and passing through said intermediate wall, a cam rotatably mounted on said shaft and secured to said other jaw, another cam rigidly secured on said shaft and adapted to engage said jaw cam for moving said other jaw toward said adjustable jaw, a collar secured to said shaft adjacent said other end wall, a handle secured to said collar for rotating said shaft manually to disengage said cams to permit said other jaw to move away from said adjustable jaw, and spring means operatively connected to said shaft and to said bracket for automatically rotating said shaft in a reverse direction when said handle is released to move said other jaw toward said adjustable jaw.

6. In a device of the class described, a clamp, comprising a bracket having a back, end walls and an intermediate wall, a jaw having a serrated rope-engaging groove movably mounted on said bracket back wall, a screw threaded through one of said bracket end walls and rotatably secured to said jaw for adjusting the position of said jaw, another jaw having a serrated rope-engaging groove complementary to said first mentioned groove movably mounted on said bracket back wall, a shaft rotatably journalled and secured at one end in said other jaw and at its other end journalled in the other end wall of said bracket, and passing through said intermediate wall, a cam rotatably mounted on said shaft and secured to said other jaw, another cam rigidly secured on said shaft and adapted to engage said jaw cam for moving said other jaw toward said adjustable jaw, a collar secured to said shaft adjacent said other end wall, a handle secured to said collar for rotating said shaft same manually to disengage said cams to permit said other jaw to move away from said adjustable jaw, and spring means operatively connected to said shaft and to said bracket for automatically rotating said shaft in a reverse direction when said handle is released to move said other jaw toward said adjustable jaw, said

spring means including a torsion spring surrounding said shaft and secured at one end to said collar and at the other end to said intermediate wall.

7. In a device of the class described, a clamp, comprising a bracket having a back, end walls and an intermediate wall, a jaw having a serrate rope-engaging groove movably mounted on said bracket back wall, a screw threaded through one of said bracket end walls and rotatably secured to said jaw for adjusting the position of said jaw, another jaw having a serrated rope-engaging groove complementary to said first mentioned groove movably mounted on said bracket back wall, a shaft rotatably journaled and secured at one end in said other jaw and at its other end journaled in the other end wall of said bracket, and passing through said intermediate wall, a cam rotatably mounted on said shaft and secured to said other jaw, another cam rigidly secured on said shaft and adapted to engage said jaw cam for moving said other jaw toward said adjustable jaw, a collar secured to said shaft adjacent said other end wall, a handle secured to said collar shaft for rotating said shaft same manually to disengage said cams to permit said other jaw to move away from said adjustable jaw, and spring means operatively connected to said shaft and to said bracket for automatically rotating said shaft in a reverse direction when said handle is released to move said other jaw toward said adjustable jaw, said spring means including a torsion spring surrounding said shaft and secured at one end to said collar and at the other end to said intermediate wall, and a tension spring connected at one end to said collar and at the other end to said bracket.

8. In a device of the class described, a clamp, comprising a bracket, a jaw having a serrated rope-engaging groove movably mounted on said bracket, a screw threaded into a part of said bracket and rotatably secured to said jaw for adjusting the position of said jaw, another jaw having a serrated rope-engaging groove complementary to said first mentioned groove movably mounted on said bracket, a shaft rotatably journaled at one end in said other jaw and at its other end in a part of said bracket, a cam rotatably mounted on said shaft and secured to said other jaw, another cam rigidly secured on said shaft and adapted to engage said jaw cam for moving said other jaw toward said adjustable jaw, an internally toothed ring gear secured to said last mentioned part for limited rotative movement relative thereto, a gear secured to said shaft in engagement with said ring gear, a handle secured to said ring gear for rotating said shaft manually to disengage said cams to permit said other jaw to move away from said adjustable jaw, and spring means operatively connected to said shaft and to said bracket for automatically rotating said shaft in a reverse direction when said handle is released to move said other jaw toward said adjustable jaw.

9. In a device of the class described a clamp, comprising a bracket, a jaw having a serrated

rope-engaging groove movably mounted on said bracket, a screw threaded into a part of said bracket and rotatably secured to said jaw for adjusting the position of said jaw, another jaw having a serrated rope-engaging groove complementary to said first mentioned groove movably mounted on said bracket, a shaft rotatably journaled at one end in said other jaw and at its other end in a part of said bracket, a cam rotatably mounted on said shaft and secured to said other jaw, another cam rigidly secured on said shaft and adapted to engage said jaw cam for moving said other jaw toward said adjustable jaw, a handle secured to said shaft for rotating same manually to disengage said cams to permit said other jaw to move away from said adjustable jaw, and a spring means operatively connected to said shaft and to said bracket for automatically rotating said shaft in a reverse direction when said handle is released to move said other jaw toward said adjustable jaw, and tension spring connected to said other jaw and to a part of said bracket on the side of said other jaw remote from said adjustable jaw.

10. A safety device for gripping a rope or the like comprising a base, a jaw movably mounted on said base, a screw threaded into a part of said base and rotatably secured to said jaw for adjusting the position of said jaw, another jaw movably mounted on said base, a shaft rotatably journaled at one end in said other jaw and at its other end in a part of said base, a cam rotatably mounted on said shaft and secured to said other jaw, another cam rigidly secured on said shaft and adapted to engage said jaw cam for moving said other jaw toward said adjustable jaw, a handle secured to said shaft for rotating same manually to disengage said cams to permit said other jaw to move away from said adjustable jaw, and spring means secured to said shaft and to said base for automatically rotating said shaft in a reverse direction when said handle is released to move said other jaw toward said adjusted jaw.

11. A safety device for gripping a rope or the like comprising a base, a jaw slidably mounted on said base, a screw threaded into a part of said base and rotatably secured to said jaw for adjusting the position of said jaw, a handle secured to said screw for manually operating same, a set screw in a part of said base for coacting with said screw for locking said screw in an adjusted position, another jaw slidably mounted on said base, a shaft rotatably journaled at one end in said other jaw and at its other end in a part of said base, a cam rotatably mounted on said shaft and secured to said other jaw, another cam rigidly secured on said shaft and adapted to engage said jaw cam for moving said other jaw toward said adjustable jaw, a handle secured to said shaft for rotating same manually to disengage said cams to permit said other jaw to move away from said adjustable jaw, and spring means secured to said shaft and to said base for automatically rotating said shaft in a reverse direction when said handle is released to move said other jaw toward said adjusted jaw.

JACK FRANKEL.
